INVENTOR

BY *Victor J. Evans*

ATTORNEY

UNITED STATES PATENT OFFICE.

PAUL MACHOWICZ, OF BROOKLYN, NEW YORK.

SHADE-SUPPORTING BRACKET.

Application filed March 25, 1925. Serial No. 18,285.

This invention relates to improvements in shade supporting brackets.

The principal object of the invention resides in a means for adjustably mounting 5 a shade roller, curtains and draperies upon a window whereby the same may be lowered to a position for admitting air into a room when the top sash of the window is lowered for ventilating purposes.

10 Another object of the invention is the provision of a means for adjustably supporting the trimming of a window which includes a pair of tracks mounted upon a window casing, and in each of which a frame is 15 slidably mounted for adjustment therealong, and which is locked in the desired adjusted position by suitable co-acting members.

20 A further object is to provide adjusting shade supporting means which is simple in construction, cheap of manufacture and easy of operation.

25 With these and other objects in view, the invention resides in certain novel construction and combination and arrangement of parts, the essential features of which are hereinafter fully described, are particularly pointed out in the appended claim, and are illustrated in the accompanying drawing, in which:—

30 Figure 1 is a front elevation of my invention in position upon a window.

Figure 2 is an enlarged vertical sectional view on the line 2—2 of Figure 1.

Figure 3 is a horizontal sectional view on 35 the line 3—3 of Figure 2.

Figure 4 is a detail perspective view of the sliding frame member.

Figure 5 is a detail sectional view of a slight modification.

40 Referring more particularly to the drawing, the reference numeral 10 designates the casing of a window, and 11 the top sash which is slidable therein. Secured to each of the front vertical sides of the casing is a track 12 which extends upward to a point adjacent the top of the casing and downward a suitable distance depending upon the desired range of adjustment for the supporting means 13.

45 The means 13 includes a U-shaped member or frame 14 having aligned notches 15 therein adjacent the corners and which receive the flanges of the tracks 12. The bight portion of the U-shaped frame is disposed 50 within the track while the legs extend horizontally therefrom for supporting a wooden

block 16. The block 16 is held between the legs by thumb screws 17 and 18 for removably mounting the said block to permit its removal or substitution should the same become worn or damaged. The block support hooks 19 and 20 which may be screwed into the block and which are adapted to support the ends of the curtain and drapery rods respectively. 60

A shade bracket 21 is held in adjusted position by the thumb nut 18 for supporting a shade roller 22. It will be understood that the means 13 on opposite sides of the casing are always diametrically opposed to support the shade roller in horizontal alignment at all times. 70

For moving the respective means 13 along the tracks 12, I provide a manipulating rod 23 having a handle 24 at one end, while the opposite end is swivelly connected as at 25 with the lower leg of the frame 14. The rod is of a length to dispose the handle 24 within the reach of the operator when the means 13 is at the extreme limit of its upward 80 movement. The swivel connection comprises an eye 26 extended from the end of the rod, and which passes through a similar eye 27 removably carried by the frame. By reason of the swivel connection, it is possible for 85 the operator to grasp both the rods for simultaneously moving both of the means 13, thus keeping the curtains and draperies from sliding along their supporting rods which movement would occur should each of the 90 means be adjusted separately.

For assuring a positive holding of each of the means 13 in its limits of movement, I provide a hook 28 on the rod for engagement with eyes 29 extending from the track 12. 95 The means 13 are held in various positions of adjustment by a binding action between the frame 14 and the track 12. The weight of the hangings causes the lower corner of the frame 15 to be forced against the rear 100 wall of the track, while the upper corner of the frame is jammed against the flanges of the track as shown in Figure 2 of the drawing. When in this position, the bight portion of the frame is disposed at a slight angle 105 with respect to the vertical longitudinal axis of the track by reason of a slight play between the frame and the track. When it is desired to move the means 13, the rod is grasped and the frame lifted to disengage 110 the hook and eye and to free the same from binding engagement with the track where

upon the supporting means may be moved to the desired position.

The invention is primarily intended for admitting air into a room from the top of a window for ventilating purposes, whereby the trimmings of the window will not tend to shut off the admission of air.

In Figure 5, I have shown a slightly modified form wherein the use of the wooden block 16 shown in the preferred form is dispensed with. In this form of the invention, the supporting hooks 19' and 20' are fastened to the top leg of the U-shaped frame in any suitable manner such as shown.

15 What is claimed as new is:—

A window shade bracket comprising a track adapted to be mounted upon a win-

dow casing, a U-shaped frame member having its legs provided with aligned notches for the reception of said track for slidable movement thereon, a block removably supported by said U-shaped frame between the legs thereof, a shade bracket adjustably supported by said frame, supporting hooks extending outwardly from said block, a manipulating member having one end swivelly connected to said U-shaped frame member, and a hook carried by said manipulating member for engagement with an eye adapted to be mounted on the window frame, substantially as and for the purpose specified.

25 In testimony whereof I affix my signature.

30 PAUL MACHOWICZ.
